UNITED STATES PATENT OFFICE.

JAMES FENTRESS, OF CHICAGO, ILLINOIS.

DIE TRACK FOR FORMING SPIRAL STEEL TUBING.

1,417,050.

Specification of Letters Patent. Patented May 23, 1922.

Application filed July 14, 1919. Serial No. 310,843.

To all whom it may concern:

Be it known that I, JAMES FENTRESS, a citizen of the United States, residing at Chicago, in the county of Cook and State of Illinois, have invented a certain new and useful Improvement in Die Tracks for Forming Spiral Steel Tubing, of which the following is a specification.

This invention relates to mechanism for making spirally wound metallic tubing well known in the art used for many purposes, among them, flexible gas pipes, between a wall fixture and a lamp on the table or the like. Such a tube is shown as 10 in exterior view in Figures 1 and 2 and in cross section in Figure 6. In the particular kind of tube shown in the drawings, the metal strip 12 of which the tube is formed is made in an S-shaped cross section shown in Figure 5 and adjacent layers or convolutions of tube enclose the rubber packing 14 clearly shown in Figure 6 which render it gas and liquid tight. Such a tube cannot be wound spirally by merely taking the piece of straight flat parallel sided metal and passing it through a straight die to give it a plain S-shaped cross section, as shown in Figure 5 and then winding on a mandrel. To make the metal wind spirally, the die must, as is well understood in the art, also be curved in the flat plane of passing metal to thereby contract one side edge of the strip or stretch the other edge (or both).

The objects of this invention are to provide a die or forming tool for use in machines automatically making this class of metallic tubing; in which the opposite edges of the metal strip are visible as it passes through the die so that trouble of any sort can be observed by the operator and dirt and loose galvanization can escape in which other exits for dirt and the like leading to the outside may be readily provided; in which the parts of the die can be made in practically only two pieces thereby rendering the die readily disassembled for examination or cleaning; and in which a minimum amount of metal is required.

The invention consists in means of carrying out the foregoing objects which can be easily and cheaply made, which is satisfactory in operation, particularly in increasing the speed at which the machine using the die may be operated and which is not readily liable to get out of order. More particularly the invention consists in the fea-

tures and details of construction hereafter more fully set forth in the specification and claims.

Referring to the drawings in which like numerals represent the same parts through the several views,

Figure 1 is a front elevation of essential parts of a machine for making the described metallic tube, the die mechanism of this invention appearing in side view.

Figure 2 is a plan view of the mechanism shown in Figure 1.

Figure 3 is a sectional detail view taken on the line 3—3 of Figure 1.

Figure 4 is a perspective view of the die mechanism proper taken from the side which is at the top of Figure 2, showing the die parts separated one from the other.

Figure 5 is as indicated, a cross section of a piece of tube material.

Figure 6 is a cross section of a tube.

The device of this invention consists essentially of two long comparatively thin metal bars or plates 16 and 18 placed approximately edge to edge with their respective metal forming or working surfaces 20 and 22 located, as shown in Figure 3, between them. These bars are, for the reason stated in the last half of the opening paragraph of the specification, bent in the curve 24 so that the delivery end 26 of the die is at right angles to the main portion of the die terminating in the entrance end 28. The parts, just described are provided on the outside of the curve 24 with the curved guard rail mechanism 30 to borrow a term from the railroad art, to hold the passing metal in the die working surfaces 20 and 22 while going around the curve 24 and for the same purpose an inner guard rail 32 is provided on the inside of curve 24. These die member bars or plates 16 and 18 are only slightly if any, wider than the finished metal strip 12 which passes between them and are so formed that what is happening to the passing metal can be clearly seen through the open space 34 (Figure 3). This access to the work is important in allowing other devices not here involved to engage the edge of the work as it passes through the machine.

This narrowness of the track also allows dirt such as loose galvanization on the edge of the work to drop out unassisted thus preventing jamming. This structure is also important in that if the finished work is slightly wider than the working tools on the

bars the excess width can stick out through the open edges of the bars without interfering with the passage of the work as necessarily takes place where the working tools are enclosed in blocks thicker than the working tools. The lower die member 16 is provided with at least one discharge notch spout 36 through which dirt or grease or the like carried by the metallic strip 12, on entering the die, may eject itself or be forcibly ejected and similar discharge passages may be provided in the upper die member, one being indicated at 38, Figure 1.

It is obvious that to form cold flat parallel sided straight metal strip material into the spiral tube of Figure 6, it is necessary that these members 16 and 18 be held rigidly spaced apart, as shown in the drawings, it being well known in the art that if die members are not so held serious trouble ensues. This result is accomplished by providing a base block or frame member 40 to which the member 16 is rigidly secured by any suitable means such, for instance, as the screws 42 and by providing a removable block 44 to which the die member 18 is rigidly attached by any suitable means as, for instance, the screw 46 and by then detachably securing block 44 to block 40 by suitable means such as a single screw 48. In the construction described, it is only necessary to remove the screw 48 for the operator to move the parts of the die from the closed position of Figure 3 to separated position of Figure 4.

Figures 1 and 2 of the drawings show the device of this invention heretofore described, mounted in working position in the machine which automatically makes the tube. These figures show at the left, fragmentary portions of the last feed wheels 50 which drive the initially plain strip of metal into and through the die and they show at the right the wheel device 52 well known in the art which rolls the metal strip 12 onto the mandrel 54 to form the finished tube 10.

The screw mechanism 56 is merely an adjustable supporting device for engaging and holding the end 26 of the die mechanism in alignment with the wheels 52.

The die of this invention has been and is in commercial use and by actual test greatly reduces the cost of dies heretofore used in machines of his class; and greatly increases the efficiency of the machine using the die, both by increasing the speed of the machine and by reducing materially time wasted in stoppages of the machine for trouble occurring in the die mechanism. The construction here shown has the advantage that the same die may be used for different sized tubes by changing the curvature of bend 24. This can be effected by annealing and bending slightly, then rehardening. Another advantage is that the die is so thin that the rubber 14 may be fed into the tube at the side of

the point 26 of the die, while in old constructions it had to go through a hole, thus causing breaks in the rubber every time a knot came along.

The die is comparatively inexpensive because the main die parts being thin can be machine made while straight and then bent to the desired curve 24, while in prior constructions formed in a thick block the track for the metal strip has to be dug by hand out of a solid block or it has to be made in additional parts fitted together, necessitating many difficult adjustments.

Having thus described my invention what I claim as new and desire to secure by Letters Patent, is:

1. In mechanism of the class described, two metal bars of considerable curved length and comparatively thin in one dimension, placed with their thin edges face to face, working surfaces for forming metal on said oppositely disposed thin faces and extending lengthwise of said metal bars, said working faces occupying substantially the whole of the thin opposing faces of the bar and means for rigidly securing said bars in position with reference to each other.

2. In mechanism of the class described, a pair of relatively thin bars of substantial length, placed edge to edge, there being formed upon the adjacent edges metal working tools spaced one from the other to shape a piece of metal passed longitudinally along between said bars, a curved bend in said bars so that one end portion is at a substantial angle to the other end, and means for detachably securing said bars in said position with reference to each other.

3. In mechanism of the class described, a pair of relatively thin bars of substantial length, placed edge to edge, there being formed upon the adjacent edges metal working tools spaced one from the other to shape a piece of metal passed longitudinally along between said bars, a curved bend in said bars so that one end portion is at a substantial angle to the other end, means for detachably securing said bars in said position with reference to each other, and guard rail mechanism adjacent to said curve for the purposes set forth.

4. In mechanism of the class described, a pair of relatively thin bars of substantial length, placed edge to edge, there being formed upon the adjacent edges metal working tools spaced one from the other to shape a piece of metal passed longitudinally along between said bars, a curved bend in said bars so that one end portion is at a substantial angle to the other end, means for detachably securing said bars in said position with reference to each other, and a guard rail on the outside of said curve, for the purposes set forth.

5. In mechanism of the class described, a

pair of relatively thin bars of substantial length, placed edge to edge, there being formed upon the adjacent edges metal working tools spaced one from the other to shape 5 a piece of metal passed longitudinally along between said bars, a curved bend in said bars so that one end portion is at a substantial angle to the other end, means for detachably securing said bars in said position with reference to each other, and a 10 guard rail on the inside of said curve for the purposes set forth.

6. In mechanism of the class described, a pair of relatively thin bars of substantial 15 length, placed edge to edge, there being formed upon the adjacent edges metal working tools spaced one from the other to shape a piece of metal passed longitudinally along between said bars, a curved bend in said bars so that one end portion is at a substantial 20 angle to the other end, means for detachably securing said bars in said position with reference to each other, and guard rails on the inside and outside of said bars 25 for the purposes set forth.

7. In mechanism of the class described, in combination with a supporting base a relatively thin, long curved bar, detachably secured to said base, a supplemental block 30 fitting on said base and detachably securable thereto, a second relatively thin long bar curved to conform to the first bar secured to said supplemental block, said parts being so arranged that the relatively thin edges of 35 said bars closely approach each other but leave a space between them on which working surfaces for forming a metal strip are formed substantially the entire width of the bars, the side edges of said space between 40 them being open for the purposes set forth.

8. In mechanism of the class described, in combination with a supporting base, a relatively thin, long bar, detachably secured to said base, a supplemental block fitting on 45 said base and detachably securable thereto, a second relatively thin long bar secured to said supplemental block, said parts being so arranged that the relatively thin edges of 50 said bars closely approach each other but leave a space between them on which work-

ing surfaces for forming a metal strip are formed, the side edges of said space between them being open, there being a substantial bend in said bars beyond the supports, and guard rail mechanism adjacent to said bed 55 for preventing the escape of metal traveling around said bend in the working surfaces between said bars.

9. In mechanism of the class described, a die member comprising a pair of relatively thin long bars correspondingly curved intermediate of their ends, each having a working surface interfitting with the working surface of the other, said working surfaces of the bars being placed on the thin 60 edges of the respective bars and extending lengthwise of the bars, and extending over substantially the entire width of the bar whereby a metal strip passing between the bars for forming thereby is constantly visible from the outside of the bar.

10. In mechanism of the class described, a pair of relatively thin long bars curved for forming a strip of metal, the thickness of the bars being substantially the thickness of 75 the formed strip and the working surfaces for forming the strips of metal being placed upon the thin edges of the bar, and means for rigidly detachably securing said bars with their working faces parallel to and 80 separated from each other, for the purposes set forth.

11. In mechanism of the class described, a die mechanism comprising a pair of comparatively long members correspondingly 85 curved between their ends spaced apart one from the other with working surfaces between them for forming metal passed therethrough along the length of said bars, means for detachably securing the bars in said position, said bars being of such a dimension 90 with reference to the work that exit passages for dirt are formed in one or both of the bars leading from the passage way to the sides of the bars, for the purposes set 95 forth.

In witness whereof, I have hereunto subscribed my name.

JAMES FENTRESS.
